UNITED STATES PATENT OFFICE.

LESLIE H. BURLIN, OF CHICAGO, ILLINOIS, ASSIGNOR TO CHICAGO HARDWARE FOUNDRY COMPANY, OF NORTH CHICAGO, ILLINOIS, A CORPORATION OF ILLINOIS.

DESIGN FOR A BACK FOR A CHAIR OR SIMILAR ARTICLE.

Application filed December 6, 1923. Serial No. 7,965. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for a Back for a Chair or Similar Article, of which the following is a specification, reference being had to the accompanying drawing, forming a part thereof.

The figure is a perspective view of a back for a chair or similar article showing my new design.

My chair back is made and sold as a complete and independent article of manufacture.

I claim:

The ornamental design for a back for a chair or similar article, as shown.

LESLIE H. BURLIN.
